UNITED STATES PATENT OFFICE.

JOHN GARDNER, OF CARNFORTH, ENGLAND.

WINDMOTOR.

Application filed May 28, 1923. Serial No. 641,925.

To all whom it may concern:

Be it known that I, JOHN GARDNER, a subject of the King of Great Britain and Ireland, and a resident of Bolton-le-Sands, 5 Carnforth, in the county of Lancaster, England, have invented certain new and useful Improvements in or Relating to Wind-motors, of which the following is a specification.

10 This invention has reference to wind-motors of the leeward type, i. e., in which the windwheel is normally to the leeward of a vertical axis about which it is free to turn to follow changes of direction of the wind 15 and about which it is adapted to move into and out of the wind according to variations in the strength or velocity of the wind.

In windmotors of the said type the movements of the windwheel into and out of the 20 wind have been effected and controlled by a governor vane mounted on a substantially horizontal axis and on one side of the vertical axis about which the whole motor turns, such vane presenting its edge to light 25 or normal wind and being turned about its axis to present a greater area to the wind as the strength of the latter increases, so as to turn the windwheel out of the wind. The governor vane has been controlled and operated by a pilot vane connected with the axis 30 of the governor vane on one side of the vertical axis, said pilot vane normally presenting a maximum area to the wind and being adapted to be deflected from its normal position by the wind as the strength thereof 35 increases, to turn the governor vane to present a greater area to the wind, against the action of restoring means tending to operate the governor vane to its normal or in- 40 operative position.

The main object of the present invention is to provide improved means of controlling and operating the governor vane which will be more sensitive in action than the pilot vane referred to.

According to this invention the governor vane is controlled and operated by means of a centrifugal governor.

Further features of the invention will be 50 apparent from the following description made with reference to the accompanying drawings, in which Fig. 1 is an elevation partly in section of one embodiment of my improvements in an apparatus for driving an electric generator, Fig. 2 an elevation on 55 the line X—X in Fig. 1, Fig. 3 a plan of

Fig. 1, Fig. 4 a fragmentary elevation illustrating the mounting of the sails upon their shaft, and Fig. 5 an elevation to a smaller scale, looking towards the left hand in Fig. 1, but with the sails turned through 90°. In Figs. 1, 2 and 3 the direction of the wind is indicated by arrows, while in Fig. 5 the direction is, of course, from the observer.

Referring to the drawings, 1 is a frame or bracket which carries the whole of the moving parts of the apparatus and which is apertured at the bottom for the passage of the supporting post 2 and is supported at the top on the post by means of a ball bearing 2^a (Fig. 2). The frame 1 is provided with bearings 1^a wherein is mounted the shaft 3 of the windwheel and with bearings 11 in which the horizontal shaft 10 of the laterally projecting governor vane 9 is mounted. The electric generator 6 geared with the shaft 3 by bevel gearing 5, is mounted on the frame 1 at the windward side of the post 2 and the several parts of the apparatus are so arranged that the whole is roughly balanced on the top of the post. Brushes (not shown) mounted at the lower end of the generator 6 co-act with slip rings 7 secured on the post from which slip rings 8 the current generated is conveyed by suitable conductors to the battery to be charged, the motor to be driven, or the like.

The windwheel is of the type comprising two diametrically opposite sails 8. The sails 8 are carried by a single transverse arm 4, preferably of wood, bored to receive the leeward end of the shaft 3, which is slotted to receive a key or feather 25. The arm 4 is also slotted at either side of the central hole to receive the key or feather 25 and to allow of the tight gripping of the shaft by the arm on the tightening up of the securing bolts 26 which pass through the key or feather, the arm 4 and side plates 27. The end of the shaft is reduced to form a shoulder and is screw threaded to receive a securing nut 28. The sails may be of plywood and be secured to the arm 4, by battens 29, Fig. 5. The required angle of weather or pitch may be imparted to the sails by appropriately beveling the surface of the arm 4 to receive the battens 29.

The shaft 10 of the governor vane 9 is illustrated as projecting laterally of the shaft 3 horizontally and normal thereto, but in some cases the shaft 10 may not be

normal to the shaft 3. The vane 9 may be mounted so that when in the normal or inoperative position it presents a thin edge to the wind, but in order to reduce friction at the bearings 11 of the shaft 10 it is preferred to give the vane a slight initial elevation, as shown in Fig. 1, so that the wind pressure always tends to turn the vane into or towards the position of maximum effect indicated in dotted lines.

For varying the position of the vane 9 between the inoperative position shown in full lines, in which the windwheel is fully in the wind, and the position of maximum effect indicated in dotted lines in which the windwheel would be turned completely out of the wind by the wind pressure on the vane overcoming the tail or rudder effect of the wheel and rotating the frame 1 on the post 2, I employ a centrifugal governor comprising weights 18 connected by flat springs 20 with a member 17 fixed upon the shaft 3, and also connected with the muff 16, slidably mounted on the shaft 3, by links 19 which are pivoted at one end to the weights 18 and at the other end to the muff 16 which moves backwards and forwards on the shaft 3 according to the radial position of the weights. On the shaft 3 is also slidably mounted the closed end 14 of a U-shaped member 13 the limbs of which are pivoted to the free ends of the levers 12 fixed on the shaft 10 of the vane 9. A ball thrust bearing 15 is arranged between the muff 16 and the end 14 of the member 13. There is also fixed on the shaft 10 a lever 21 having the properties of a fusee, by which a force of uniform strength may oppose with increasing effect the expansion of the governor weights 18. To the fusee lever 21 and near the shaft 10 is connected one end of a chain or band 22 the other end of which is connected to the periphery 23 of a drum provided with a restoring spring which tends to keep the vane 9 in its inoperative position. The drum 23, may, however, be a pulley over which the chain or band 22 passes to a weight or to a spring attached to the frame. In the position shown, the fusee lever will be acted upon by the spring only slightly to oppose expansion of the governor weights, but as the expansion increases, the additional leverage afforded by the movement of the fusee lever will afford the spring greater leverage to counteract the increasing centrifugal force developed by the higher speed and greater leverage of the governor weights 18.

While it is preferred that the restoring spring or weight should act upon the vane shaft 10 through the medium of a fusee, the latter may be dispensed with.

The mode of operation of the governing mechanism is as follows:—The opposing force of the restoring spring being such

that, in a wind of medium strength, the governor is partially expanded and the vane 9 in an intermediate position, the windwheel will be partially turned out of the wind by the pressure of the wind upon the vane 9 70 overcoming the tail or rudder effect of the wheel. A reduction of wind strength will cause a diminution of the speed of the windwheel; the governor will contract under the influence of the restoring spring; the vane 75 9 will move towards the inoperative position; and the tail or rudder effect of the windwheel due to its leeward position on the post will bring the wheel more nearly normal to the direction of the wind, thus offering a greater area of sail to be acted upon. With an increase of wind strength the governor will expand beyond an intermediate degree; its muff 16, acting through the U 80 connection 13—14 upon the arms 12 will 85 cause the vane 9 to present a greater area; the tail effect of the windwheel will be further overcome, and the wheel turned to a greater extent out of the wind; and the wind will impinge upon a smaller sail area, 90 thus reducing the speed to the number of revolutions for which the governing apparatus is adjusted.

For the purpose of stopping the windmotor there is provided an arm 24, attached 95 to the vane shaft 10, by which the vane 9 may be manually pulled into the vertical position indicated in Fig. 1 in dotted lines, when there will be offered to the wind a vane area so great as to completely overcome the rudder effect of the sails, which will then be forced completely out of the wind. The arm 24, which may conveniently be combined with one of the arms 12, is drawn down by a cord 30, extending below 100 to a position convenient for the operator, the cord being then held in position by a cleat or the like until it is desired to re-start the windmotor.

With the object of preventing any rotation of the windwheel which may occur whilst the vane is in its fully operative, or vertical position, a drum may be secured to the shaft, between the bearings 1^a on the frame 1, so as to rotate with the shaft, and there may be carried on the vane shaft 10, in a position between the two levers 12, an arm to which is attached a brake-shoe which will press upon the drum when the stopping cord 30 is pulled and the vane 9 is in the vertical 110 115 120 position.

The dynamo employed in this invention when fitted in the preferred situation on the frame 1 as illustrated is offset from the post 2, its armature shaft being parallel to, but 125 not coincident with, the vertical axis afforded by the post 2. Simplified construction is permitted by this arrangement, and the balancing of the complete mechanism upon the vertical axis, tending to free and 130

prompt movement in response to variable winds, is facilitated. The vertical shaft of great length and coinciding with the vertical axis of the apparatus as hitherto proposed for the purpose of driving electric generators, calls for the provision of several bearings or guides to prevent whirling of the long vertical shaft. The compact main frame or bracket provided by the present invention, while reducing to a minimum the number of bearings required, also provides convenient housing for ball or roller bearings for the limited number of moving parts, thus abolishing the need of frequent lubrication. Further, the lightness gained by the construction and arrangement detailed permits the use of a less costly tower than usual to support the post 2, a mere mast, suitably stayed by guy ropes, being ample for the purpose, or, where an outbuilding is available, the post 2 may be supported on the ridge of the structure.

Instead of a vertical dynamo being employed, driven through bevel gearing as shown in the drawings, the generator may have its armature shaft horizontally placed and be driven from the shaft 3 through spur gearing, chain gearing or the like.

While the centrifugal governor has been described as turning with the windwheel shaft 3, it may be carried by an independent spindle geared to said shaft. Or the governor may be mounted upon an extension of the armature shaft of the dynamo.

What I claim as my invention and desire to secure by Letters Patent is:—

1. In a windmotor of the leeward type, a rotatable windwheel mounted for bodily movement about a vertical axis, a governor vane extending laterally of the axis of rotation of the windwheel and mounted for rotation therewith about the vertical axis, said vane being adjustable to present variable effective surface areas to the action of the wind, and a centrifugal device driven by the windwheel for varying the surface area of the vane which is exposed to the wind in proportion to the speed of the windwheel.

2. In a windmotor of the leeward type, a rotatable windwheel mounted for bodily movement about a vertical axis, a governor vane extending laterally of the axis of rotation of the windwheel and mounted for rotation therewith about the vertical axis, said vane being adjustable to present variable effective surface areas to the action of the wind, and a centrifugal device driven by the windwheel for varying the surface area of the vane which is exposed to the wind in proportion to the speed of the windwheel, said vane in its normal inoperative position having a small surface area exposed to the wind.

3. In a windmotor of the leeward type, a rotatable windwheel mounted for bodily

movement about a vertical axis, a governor vane extending laterally of the axis of rotation of the windwheel and mounted for rotation therewith about the vertical axis, said vane being rotatable between a position 70 edgewise to the wind and a position broadside to the wind for presenting variable effective areas to the action of the wind, and a centrifugal device driven by the windwheel for rotating the vane to various extents between said positions for presenting to the wind an effective area of the vane which is proportional to the speed of rotation of the windwheel.

4. In a windmotor of the leeward type, a 80 rotatable windwheel mounted for bodily movement about a vertical axis, a governor vane extending laterally of the axis of rotation of the windwheel and mounted for rotation therewith about the vertical axis, said vane being rotatable between a position 85 edgewise to the wind and a position broadside to the wind for presenting variable effective areas to the action of the wind, and a centrifugal device driven by the windwheel 90 for rotating the vane to various extents between said positions for presenting to the wind an effective area of the vane which is proportional to the speed of rotation of the windwheel, said vane when edgewise to the 95 wind having a slight inclination to the direction of the wind so as to present a small surface area thereto.

5. In a windmotor of the leeward type, a 100 rotatable windwheel mounted for bodily movement about a vertical axis, a governor vane extending laterally of the axis of rotation of the windwheel and mounted for rotation therewith about the vertical axis, said vane being adjustable to present variable 105 effective surface areas to the action of the wind, and a centrifugal device responsive to the speed of the windwheel for varying the surface area of the vane which is exposed to the wind in proportion to the speed of the 110 windwheel.

6. In a windmotor of the leeward type, a 115 rotatable windwheel mounted for bodily movement about a vertical axis, a governor vane extending laterally of the axis of rotation of the windwheel and mounted for rotation therewith about the vertical axis, said vane being rotatable between a position 120 edgewise to the wind and a position broadside to the wind for presenting variable effective areas to the action of the wind, a centrifugal device driven by the windwheel for rotating the vane to various extents between 125 said positions for presenting to the wind an effective area of the vane which is proportional to the speed of rotation of the windwheel, and means constantly urging the vane toward its position in which it is edgewise to the wind, said means presenting an increasing resistance to the action of the 130

centrifugal device in rotating the vane toward a position broadside to the wind.

7. In a windmotor of the leeward type, a rotatable windwheel mounted for bodily movement about a vertical axis, a governor vane extending laterally of the axis of rotation of the windwheel and mounted for rotation therewith about the vertical axis, said vane being rotatable between a position ¹⁰ edgewise to the wind and a position broadside to the wind for presenting variable effective areas to the action of the wind, a centrifugal device driven by the windwheel for rotating the vane to various extents between said positions for presenting to the wind an effective area of the vane which is proportional to the speed of rotation of the windwheel, and means constantly urging the vane toward its position in which it is edgewise to the wind, said means including a fusee device for presenting an increasing resistance to the action of the centrifugal device in rotating the vane toward a position broadside to the wind.

25 8. In a windmotor of the leeward type, a rotatable windwheel mounted for bodily movement about a vertical axis, a governor vane extending laterally of the axis of rotation of the windwheel and mounted for rotation therewith about the vertical axis, said vane being adjustable to present variable effective surface areas to the action of the wind, a centrifugal device driven by the

windwheel for varying the surface area of the vane which is exposed to the wind in ³⁵ proportion to the speed of the windwheel, and yieldable means constantly opposing the operation of the vane by the centrifugal device and tending to return the vane to the position which it occupies when the windwheel is not rotating.

9. In a windmotor of the leeward type, a rotatable windwheel mounted for bodily movement about a vertical axis, a governor vane extending laterally of the axis of rotation of the windwheel and mounted for rotation therewith about the vertical axis, said vane being adjustable to present variable effective surface areas to the action of the wind, a centrifugal device driven by the ⁴⁵ windwheel for varying the surface area of the vane which is exposed to the wind in proportion to the speed of the windwheel, and yieldable means constantly opposing the operation of the vane by the centrifugal device and tending to return the vane to the position which it occupies when the windwheel is not rotating, said means including a fusee device for varying the surface area of the vane which is exposed to the wind in ⁵⁰ proportion to the speed of the windwheel, and yieldable means constantly opposing the operation of the vane by the centrifugal device and tending to return the vane to the position which it occupies when the windwheel is not rotating, said means including a fusee device for presenting variable effective areas to the action of the wind, a centrifugal device driven by the ⁵⁵ windwheel for varying the surface area of the vane which is exposed to the wind in proportion to the speed of the windwheel, and yieldable means constantly opposing the operation of the vane by the centrifugal device and tending to return the vane to the position which it occupies when the windwheel is not rotating, said means including a fusee device for increasing the effective opposition to the increasing action of the centrifugal device which is caused by an increasing rate of rotation of the windwheel.

In witness whereof I have hereunto set my hand.

JOHN GARDNER.
